GRAIN-HEATER CONTROLLER.

1,158,623.

Specification of Letters Patent.

Patented Nov. 2, 1915.

Application filed September 3, 1913. Serial No. 787,846.

To all whom it may concern:

Be it known that I, ALLEN C. BRANTINGHAM, a citizen of the United States, residing at Toledo, Lucas county, Ohio, have invented a new and useful Grain-Heater Controller, of which the following is a specification.

This invention relates to devices for uniformly treating material.

This invention has utility when embodied in grain heaters having a plurality of ways.

Referring to the drawings: Figure 1 is a side elevation with parts broken away showing an embodiment of the invention in a grain heater; Fig. 2 is a plan view thereof with parts broken away to show the various features thereof; Fig. 3 is a detail view on an enlarged scale showing a tilting hopper and the driver therefor; Fig. 4 is a detail view in side elevation of the driving link; Fig. 5 is a side elevation of one of the hoppers; and Fig. 6 is a bottom plan view thereof.

The material to be treated is received in the upper delivery device 1 forming a receiving chamber or hopper with openings 2 therethrough from which the material may directly flow into the tubes or parallel ways 3 of the grain heater. These tubes 3 are mounted in the heads 4, 5, carried by the cylindrical drum 6 of the heater, said heater having the insulating jacket 7. The heat medium is supplied by means of the intake pipe 8 and is discharged therefrom through the duct 9, which may be condensed steam when steam is used as the heating medium.

Carried by the outer shell of the insulating jacket are brackets 11 upon which may rest springs 12 abutting against nuts 13 as the springs and nuts surround the rods 14 adjustably connected to yieldably poised the delivery device 1. As there is an accumulation of material in the delivery device 1, the springs 12 are compressed and in this settling down of the rods 14, the platform 15 is also carried downward and farther away from the ways 3. This platform 15 has slats 16 and intermediate slots 17. The slats 16 are normally in alignment with the ways 3 so that the grain tumbling about the chain 18 in its passage through the heating ways 3 may have its through travel checked or impeded when it strikes the slat 16. Upon the settling of the platform 15 due to accumulation of grain in the delivery hopper 1, greater space between the ways 3 and the

slats 16 permits a greater rate of flow of material through said ways and accordingly this automatic adjustment to care for material flow is an automatic means for varying the treating rate by varying the flow through the ways 3. The material passing through the slots 17 in the platform 15 is collected by the hopper 19 for a common discharge. Said hopper 19 is suspended from the heater proper by the brackets 19'. As an additional effective flow checking or varying means, a continuous drive device is adopted. The pulley 20 is continuously driven from the source of power to rotate the shaft 21 on which said pulley is mounted. Said shaft 21 is carried by brackets 22, 23 mounted on the heater. The shaft 21 has the crank wheel 24 carrying the wrist pin 25. This wrist pin 25 has the block 26 reciprocable in the slot 27 in the rotation of the shaft 21 and effective to drive the link 28 as loosely suspended by the links 29 carried by the brackets 30 mounted in the lower diaphragm 5 of the heater. This link 28 has notches 31 therein which engage pins 32 of the material deflectors or oscillating hoppers 33 having their pivot pins 34 mounted in brackets 35 attached to the lower heater diaphragm 5. These hoppers 33 may have divisions 36 therein as separate compartments for the different ways or tubes 3 in registry therewith.

In operation material received in the member 1 will flow therethrough and be distributed and pass through the several ways 3 of the heater for uniform treatment. The difficulty to overcome is excessive flow through certain of the ways with a relatively retarded flow through others which may result in excessive heating or treatment of the slow flowing material and insufficient treatment of the more rapid flow. In the device as disclosed there is provision made for checking material flow, thereby insuring intermittent greater velocity flow rate or such checking control that high momentum is avoided. Congestion of material in the receiving hopper 1 will weigh down this hopper to move the platform 15 away from the lower ends of the tubes 3 and thus according a larger clearance between the ends of the ways 3 and the slats 16 of the platform 15 permitting a greater flow rate to catch up with the contents of the hopper 1. This is desirable, as in practice these heat-

ers may then be placed in a mill to care for a stream of material as demanded by the circuit following or as cared for by the various machines preceding the heater. While 5 the heating may be adjusted by the heating medium supply, adjustments may be made as to the flow rate by adjusting the nuts on the rods 14 to bring about the various positions of the platform. The continuous driving means or wheel 20 effecting a continuous reciprocation of the link 28 serves to simultaneously rock the deflectors or hoppers 33 so that the material may be directed away from the slats 16 through the slots 17 of 10 the platform, thereby increasing the flow rate at such intervals as the hoppers direct toward the slots 17. The automatic governing from the receiving hopper 1 coacts directly with these oscillating hoppers or deflectors 33 in varying the clearance therebetween and accordingly varying the possibility of flow. As the platform has a movement only to and from the heater in this 15 automatic control, the clearance between 20 said platform and the heater is such that there is no material impediment to the operation of the oscillating hoppers and no material is thus liable to injury. The parts are readily removable under all conditions 25 and a further insurance of delicacy and accuracy of control. In the event the mill is shut down, there need be no injury to material on account of being overheated by being left in the heater, for the crank wheel 30 may be readily so thrown that the hoppers 33 will be in a spill position through the slots 17, thus permitting the material to 35 flow out of the hopper.

What is claimed and it is desired to secure 40 by Letters Patent is:

1. A treating device embodying a plurality of ways for material flow, baffle means for said ways and flow checking means for the material including material deflectors, 45 and driving means to actuate the deflectors.
2. A treating device embodying parallel ways for material flow, and flow checking means for the material including a pivotally suspended material deflector, and driving 50 means for oscillating said deflector.
3. A treating device embodying a plurality of ways for material flow, a slatted platform below said ways, and means for moving said platform toward and from the ways 55 to vary material flow through said ways.
4. A treating device embodying a plurality of ways for material flow, a slotted platform below said ways, and automatic means for moving said platform toward and from

the ways to vary material flow through said 60 ways.

5. A treating device embodying parallel series of ways for material flow, a platform having a slat for each series of ways, said platform disposed below said ways, a material flow actuated delivery device to said ways above said ways, and connections from the delivery device to move the platform toward and from the ways to vary material flow through the ways. 65

6. A treating device embodying a plurality of ways for material flow, and flow checking means for the material including pivoted hopper mechanism disposed below said ways. 70

7. A treating device embodying a plurality of ways for material flow, said ways having extension means at their lower ends, a platform having slats adjacent said extension means, and driving means effecting relative movement between said extension means and platform slats to vary material flow through said ways. 75

8. A grain heater embodying a plurality of ways for material flow, flow checking 80 means for the material including pivoted hopper mechanism, and continuous driving means for said hopper mechanism.

9. A grain heater embodying first means having a passageway therethrough, a platform below said passageway and spaced therefrom, and driving means for causing relative lateral movement between the first means adjacent the platform and the platform for crowding material from the passageway off the platform. 90

10. A grain heater embodying first means having a passageway therethrough, a platform below said passageway and spaced therefrom, driving means for causing relative lateral movement between the first means adjacent the platform and the platform for crowding material from the passageway off the platform, and automatic controlling means for varying the amount of 100 material crowded off the platform. 105

11. A treating device embodying a way for material flow, and flow checking means for the material including a pivotally suspended material deflector, and driving means 110 for oscillating said deflector.

In witness whereof I hereunto set my hand in the presence of two witnesses.

ALLEN C. BRANTINGHAM.
